CLAIM

The ornamental design for a storage system, as shown and described.

DESCRIPTION

FIG. 1 is a perspective view of a storage system showing our new design;

FIG. 2 is a side elevational view thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a perspective view of a second embodiment which shows a four-bin storage system;

FIG. 8 is a front elevational view thereof;

FIG. 9 is a side elevational view thereof;

FIG. 10 is a rear elevational view thereof;

FIG. 11 is a top plan view thereof;

FIG. 12 is a bottom plan view thereof; and,

FIG. 13 is a perspective view of a third embodiment of a storage system. The jagged broken lines form no part of the claimed design and the subject matter between the jagged lines is broken away to disclose indeterminate length and the storage system may include two or more bins.

The broken-line disclosure of elements in the views is for illustrative purposes only and forms no part of the claimed design.
